UNITED STATES PATENT OFFICE.

ROBERT C. HULL, OF PHILADELPHIA, PENNSYLVANIA.

STARTER FOR EXPLOSIVE-ENGINES.

1,050,739.

Specification of Letters Patent. Patented Jan. 14, 1913.

Application filed August 26, 1912. Serial No. 716,992.

To all whom it may concern:

Be it known that I, ROBERT C. HULL, a citizen of the United States, residing in the city of Philadelphia, county of Philadelphia, and State of Pennsylvania, have invented a new and useful Starter for Explosive-Engines, of which the following is a specification.

My invention relates to a starter for explosive engines, such as gas engines, gasoline engines, and the like, which are not self starting but require to be "cranked," or "turned over" to cause a sucking into the cylinder or cylinders of an explosive mixture and the compression thereof; this mixture when ignited by the usual ignition means forcing the piston or pistons forward to deliver to the crank shaft the initial impulses as a result of which the engine itself draws or sucks in and compresses the explosive mixture automatically causing automatic continued operation of the engine.

My invention relates particularly to electro-magnetic or electro-dynamic means for starting an explosive engine, the electro-magnetic or electro-dynamic means converting electrical energy into mechanical energy for "cranking" or "turning over" the explosive engine for the purposes above described.

As early as the year 1886, I believe, it was proposed to impart the initial movement to the piston or pistons of an explosive engine by an electric motor, comprising relatively rotating armature and field magnet, the rotatable member of the motor, as the armature, being directly secured upon the engine crank shaft or suitably geared thereto for engine starting purposes. And even at the present time, particularly with regard to the explosive engines employed on automobiles or like motor vehicles, such an electric motor is resorted to for engine starting purposes, a suitable source of electric energy being provided to drive the motor. Such an electric motor is well understood to comprise an armature having the usual commutator with brushes bearing thereon, the resultant relative movement between brushes and commutator causing the progressive shifting of the magnetic poles of the armature, produced by the current in its winding, such progression of the magnetic poles taking place with respect to the body of the armature itself. And it is further charac-

teristic of such an electric motor that the relative movement between the brushes and commutator corresponds precisely with the relative movement between armature and field magnet, because the commutator is in fixed relation with the armature and the brushes in fixed relation with respect to the field magnet. From such an electric motor and all other forms of starters my invention is sharply contrasted, in that I employ as the rotor of my electro-dynamic means a member which exhibits magnetic poles which remain substantially fixed with respect to the body of the rotor, and such magnetic poles therefore rotate with the same; and as stator I employ a magnetic system in which the magnetic poles progress with respect to the body of the stator. And my invention is further contrasted in that the switching or commutating means for causing the progression of the magnetic poles in the stator may be detached or dismembered from the electro-dynamic device and removed to any suitable point, as upon the dash board of an automobile, where, in operation, such commutating or switching means may be operated solely at the will of the driver and are not necessarily driven as in an ordinary electric motor in perfectly definite relation with respect to the moving element of the motor.

In one of its aspects my invention may be viewed as employing an electric motor dismembered to the extent that the moving part of the commutator mechanism does not necessarily or at all times rotate in fixed relation with and is not driven by the rotating element of the motor but may be located at a distance from the motor at a point where the control is to be exercised and there moved at the will of the operator to cause relative movement between the rotating and stationary elements of the motor, without as in the case of an ordinary motor movement of the movable part of the commutator mechanism by the rotating element of the electro-dynamic means.

In another of its aspects my invention may be viewed as employing an electric motor dismembered to the extent that the moving part of the commutator mechanism, while it may rotate in fixed relation and be driven by the rotating element of the motor, is not necessarily always mechanically and electrically in connection with the fixed part

of the commutator mechanism, for, by my invention, these two parts may be mechanically and electrically connected at the will of the operator.

5 A further feature of my invention resides in the fact that the winding of the rotor is traversed by a relatively heavy or large current admitted to such winding through collectors and slip rings whose only function 10 is to maintain electrical communication and not to commutate, with the result that troubles attendant upon the use of a commutator and brushes for heavy currents forming a part of the armature of an ordinary electric motor are not encountered; with a relatively small current in the stator, this being the current which is controlled and commutated.

As is well understood with respect to an 20 explosive engine, the negative torque offered by the same during the "cranking" or "turning over" for starting purposes, is not uniform, but passes through a more or less sharply defined maximum and falls away 25 again to lesser values. By my invention, though I do not limit myself thereto, I may employ electro-dynamic means which will produce a non-uniform torque having well defined maximum points. And these points 30 of maximum positive torque shall preferably occur substantially simultaneously with the maximum negative torque exerted in opposition by the engine. The number of points of maximum positive torque developed 35 by the electro-dynamic means may be greater than the number of points of maximum negative torque exerted in opposition by the engine, but the former points may always be a multiple of the latter points so 40 that in all cases one of the former points shall occur substantially simultaneously with one of the latter points. And I prefer that the positive torque developed by the electro-dynamic means shall always be at 45 least as great as the negative torque of the engine exerted simultaneously therewith.

My invention resides in the apparatus for starting an explosive engine herein described.

50 My invention resides in the features hereinafter described and claimed.

For an illustration of some of the forms my invention may take, but without limiting my invention thereto, reference is to be had 55 to the accompanying drawings, in which:

Figure 1 is a longitudinal cross-sectional view, some parts in elevation, through a part of an automobile or similar motor vehicle. Fig. 2 is a diagrammatic view illustrating the circuits of and means for control of one form of electro-dynamic starter. Fig. 3 is a diagrammatic view of a modified form of starter and its control circuits. Fig. 4 is a diagrammatic view of a further modification of the electro-dynamic starter and

its control circuits. Fig. 5 is a graphic representation of the torque curve of a single cylinder of an explosive engine, as of a four cylinder engine, and a torque curve of an electro-dynamic starter therefor. Fig. 6 70 is a graphic representation of similar torque curves of a six cylinder engine and of a starter therefor. Fig. 7 is a diagrammatic view of a modified form of starter system. Fig. 8 is a fragmentary view illustrating 75 structure of the commutating mechanism of Fig. 7.

Referring to Fig. 1, the frame or chassis 1 of an automobile or like vehicle has secured thereto the explosive engine E here 80 illustrated, by way of example merely, as having four cylinders 2, 3, 4, and 5, the engine E being inclosed in the hood 6 extending from the dash board 7 to the radiator 8. Upon the shaft 9 of the engine is 85 secured the fly-wheel 10, which, however, may be omitted if desired. Secured upon the shaft 9 is the rotor element 11 of the electro-dynamic starter, the same being surrounded by the stator member 12 provided 90 with lugs 13 resting upon and secured to the frame 1. Or these lugs 13 may rest upon and be secured to or integral with the engine bed, so that the engine and electro-dynamic starter may be removed as a unit. 95 Between the engine shaft 9 and the driving shaft 14, leading to the running gear, not shown, may intervene the clutch comprising the driving member 15 and the driven member 16 operated by any suitable means 100 as the lever 17 near the seat 18 of the driver, near which are disposed also the usual steering wheel 19 and other control members 20 and 21. Upon the dash board 7, or at any other suitable point within reach of the 105 driver, are disposed the switch 22 and the switching or commutating apparatus 23 inclosed within the casing 24 and disposed upon the base 25, the crank 26 disposed outside of the casing 24 for operation by the 110 driver as hereinafter described. At any suitable place on the automobile or vehicle is mounted any suitable source of current such as a storage battery 27. Referring now to Fig. 2 one arrangement of my electro-dynamic starter and its control are illustrated. 115 Here the rotor 11, secured upon the engine shaft 9, as by a spider or other suitable means, not shown, comprises a core 11 of iron or other suitable magnetizable material upon 120 which is disposed a winding or conductor 28 with which connection is made through conductor 29 permanently connected to the slip ring 30 upon which bears a brush 31 in electrical communication through conductor 32 with one terminal of the source 27. At a diametrically opposed point on the winding 28 permanent connection is made 125 through conductor 33 with the slip ring 34 upon which bears the brush 35 which con- 130

nects with conductor 36 with one terminal 37 of the switch 22 whose other terminal connects to the remaining terminal of the source 27. The slip rings 30 and 34 are insulated from each other and rotate with the rotor 11.

- The stator 12 comprises the ring or yoke 38 of iron or other suitable magnetic material carrying the four poles 39, 40, 41, 42 each provided with a magnetizing coil 43. These coils 43 are here shown as connected in series with each other and all wound in the same direction with respect to the poles upon which they are disposed.
- From a point between one pair of coils a conductor 44 extends to a segment 45 of the commutator or switching apparatus 23. From a point between another pair of coils the conductor 46 extends to a segment 47; from a point between another pair of coils extends the conductor 48 to another segment 49; and similarly from a point between the remaining pair of coils extends a conductor 50 to the segment 51.
- The crank or lever 26 is secured to the shaft 52 carried by and rotatable with respect to the base 25 carrying the segments 45, 47, 49 and 51. Insulated from each other and rotatable with the shaft 52 and lever 26 are the slip rings 53 and 54 upon which bear the brushes 55 and 56, respectively, the brush 55 being connected through conductor 57 with one terminal of the source 27 and the brush 56 connected through conductor 58 with switch contact 37. Movable with the shaft 52 and handle 26 are the brushes 59 and 60, insulated from each other, and electrically connected respectively with the slip rings 53 and 54.
- Upon closure of the switch 22 upon contact 37 current will flow from the lower, for example, positive terminal of the source 27 through conductor 32, brush 31, slip ring 30, conductor 29, through both halves of the winding 28, returning through conductor 33, slip ring 34, brush 35, conductor 36, through switch 22 to the negative terminal of the source 27. The flow of the current through the winding 28 magnetizes the core 11 of the rotor to exhibit north and south poles on opposite ends of a diameter, which poles remain in substantially the same position with respect to the core 11 during its rotation.
- Due to the closure of the switch 22 current also flows from the lower terminal of the source 27 through conductor 57, brush 55, through slip ring 53, brush 59, segment 47, conductor 46, to the point *a* where it divides flowing through the right hand and lower coils 43 in series to the point *b*, and flowing also through the upper and left hand coils 43 to the point *b* thence through conductor 50 to segment 51, through brush 60, slip ring 54, brush 56, conductor 58, through the switch 22 to the remaining terminal of the source 27. In consequence the faces of the poles 40 and 41 will exhibit south poles, for example, while the faces of the poles 39 and 42 will exhibit north poles. The axis of the magnetic field of the stator extends in such case at 45° with the horizontal from a point midway between the poles 39 and 42 through a point midway between the poles 40 and 41 as indicated by the arrows 61. The direction of the axis of the field of the rotor 11 extends in the direction of the arrows 62. There will then be a reaction between rotor and stator producing motion of the rotor 11 in a clockwise direction as viewed in Fig. 2 tending to bring these magnetic axes of the stator and rotor into coincidence. This reaction produces a torque on the shaft 9 rotating the same in clockwise direction when viewed from the right hand end Fig. 1. The movement of the rotor 11 however will not continue, as in an ordinary electric motor having its commutator and brushes directly attached to it and causing relative shifting of the field of the armature with respect to itself in opposite direction to the rotation of the armature and to exactly the same extent of the rotation, whereby the armature continues to revolve. The rotor 11 will come to rest unless the handle 26 is moved to carry the brushes 59 and 60 into contact with segments 49 and 45, and in doing so current will flow from the source 27 through conductor 57, brush 55, slip ring 53, brush 59, segment 49, conductor 48 to the point *d* where it divides, part going in series through coils 43 on poles 39 and 40 to the point *c* and part passing in series through the coils 43 on poles 42 and 43 to the point *d*. Now the faces of poles 42 and 41 exhibit south poles, while poles 39 and 40 exhibit north poles. In other words the axis of the magnetic field of the stator has shifted in a clockwise direction through 90°. But the axis of the magnetic field of the rotor has remained substantially constant with respect to the rotor body and in consequence the rotor is rotated through a further 90°. And so on for the successive positions of the handle 26, moved in clockwise direction, Fig. 2, the rotor revolves 90° for each successive position of the handle 26, turning the shaft 9 of the engine which will start, its opposing torque having been overcome by the rotor 11, it being assumed of course that the ignition apparatus, not shown, has been set into operation and the throttle, not shown, has been opened. After the engine is started the switch 22 may be opened until it is again necessary to start the engine.
- From the construction illustrated in Fig. 2 it will be noted that the torque exerted upon the shaft 9 by the rotor 11 is not constant for all positions of the rotor 11. It is apparent that for one revolution of the shaft 130

9 there are four positions at which the torque is a maximum, and four alternate positions at which it is a minimum. The rotor is so placed as to its angular position upon 5 the shaft 9 with respect to the engine cranks that for every maximum occurring in the negative torque of the engine there will simultaneously occur a maximum in the torque of the rotor, the torque exerted by the 10 rotor 11 upon the shaft 9 at such time being in excess of the negative torque exerted upon the shaft 9 on the engine at the same time.

From the foregoing it is apparent that 15 instead of the driver getting out of the machine to crank the engine by hand, he may remain seated in the machine and move the crank 26 in proper direction and the rotor 11 will execute movements following the 20 movements of the crank 26, to crank the engine. And it is further apparent that in this arrangement my electro-dynamic starter does not operate like the ordinary electric motor which continues to rotate so long as 25 it remains in communication with a source of energy. Notwithstanding the closure of the switch 22 the rotor 11 will not continue to rotate, because the brushes 59 and 60 are mechanically independent of the rotor and 30 are not shifted synchronously with it, as is the case of an ordinary electric motor where the brushes and commutator are mechanically shifted with respect to each other in synchronism with the movement of the movable motor element.

In Fig. 3 I have shown the stator ring 38 carrying eight poles 63, 64, 65, 66, 67, 68, 69, and 70 having thereon coils 63' to 70' respectively. The common terminals of coils 40 63' and 64' are connected by conductor 71 with the common terminals of the coils 67' and 68' and with segment 49 of the commutating apparatus. Similarly the common terminals of the coils 63' and 70' are connected by conductor 72 with the common terminals of the coils 67' and 66' and with the segment 51. Similarly the common terminals of the windings 70' and 69' are connected by conductor 73 with the common 50 terminals of coils 66' and 65' and with the segment 45. And similarly the common terminals of the coils 68' and 69' are connected through conductor 74 with the common terminals of coils 64' and 65' and the segment 47. The rotor 11 in this case has in place 55 of the two windings shown in Fig. 2, four windings 28, each extending through a quadrant only diametrically opposite points of the winding being connected to one slip 60 ring 30 while diametrically opposite points, at right angles to the first named points, are connected to the slip rings 34 and through the respective brushes 35 and 31 with the source 27, when the switch 22 is closed. In 65 consequence the rotor exhibits two north

poles and two south poles, the axis of one pair of these poles being at right angles to the axis of the other pair.

When the switch 22 is closed and the handle lever 26 rotated, the rotor will follow in its movements the movements of the lever 26, its magnetic poles remaining substantially fixed with respect to the rotor. The stator, however, due to the connections of the windings as described, exhibits two 70 neighboring north poles, with two neighboring north poles diametrically opposite; also two neighboring south poles with two 75 neighboring south poles diametrically opposite. As the handle 26 is rotated through 80 90° the magnetic axes of the stator are rotated through only 45°, with the result that the handle 26 must make two complete revolutions for one complete revolution of the rotor 11. Here again the arrangement is 85 such that the torque of the rotor 11 has periodically recurring maxima and minima and, as previously stated, a maximum torque exerted by the rotor 11 shall occur substantially simultaneously with the maximum 90 negative torque by the shaft 9 exerted thereon by the engine. And as in the previous case the rotation of the handle 26 causes a rotation of the shaft 9 for engine starting purposes.

In Fig. 4 the stator ring 38 carries six poles 75, 76, 77, 78, 79, and 80 carrying respectively the magnetizing coils 75' to 80'. In this case the switching mechanism has six segments 81, 82, 83, 84, 85 and 86. The 100 segment 81 is connected through conductor 87 with the common terminal of the coils 75' and 80'; segment 82 is connected through conductor 88 with the common terminals of coils 79' and 80'; segment 83 is connected through conductor 89 with the common terminal of coils 78' and 79'; segment 84 is connected through conductor 90 with the common terminal of coils 77' and 78'; segment 85 is connected through conductor 91 105 with the common terminals of coils 76' and 77'; and segment 86 is connected through conductor 92 with the common terminals of coils 75' and 76'. The rotor is similar in 110 its winding to that shown in Fig. 2. Here a sixth of a revolution of the handle 26 causes a shifting of the magnetic axis of the stator through a sixth of a revolution, that is, through 60° with respect to the 115 stator. In the arrangement of Fig. 4 three 120 neighboring poles simultaneously exhibit like polarity while the three opposing poles simultaneously exhibit like but opposite polarity. Here again the torque of the rotor 11 has maxima and minima and it is preferred that a maximum torque by rotor 11 occurs simultaneously with maximum negative torque by the engine.

In Fig. 5 ordinates represent torque values and abscissæ represent time or an-

gular positions of the engine crank shaft. The lower curve P represents, in general, the thrust against an engine crank, or represents generally the torque of one cylinder of a four cylinder engine. The torque increases from the point *h* to a maximum at the point *k* and diminishes again to the point *l*. The upper curve Q represents the torque curve of a rotor of an electro-dynamic starter involving one form of my invention. Here it will be noted that a maximum occurs at the point *m* coinciding substantially in time with the maximum *k* of the engine torque. And the points *n* of minimum torque represent torques substantially equal to or larger than the maximum torque *k*.

In Fig. 6 the lower curve P' represents the combined crank thrusts of two cylinders of a six cylinder engine during compression period and the upper curve Q' is the torque curve of my electro-dynamic starter when having six poles, and commutator of six segments, and rotor, all as illustrated in the example of Fig. 4. Here again a maximum *m'* occurs substantially simultaneously with the maximum *k'*. It is to be understood however that my invention is not limited to starters exhibiting with respect to the engine the relations exemplified in Figs. 5 and 6 for the relative values of the torques; and the two curves in each figure may be other than indicated. But as stated it is preferred that a maximum torque be exerted by the starter substantially simultaneously with the occurrence of the maximum opposing torque on the part of the engine shaft.

In Fig. 7 is shown a form of starter whereby the operator need not turn the brush crank 26, of Fig. 2 for example, but in which one element of the commutator moves in synchronism or definite relation with the rotor, the other element of the commutator being stationary as regards rotation, and capable of connection and disconnection electrically and mechanically from the rotating element of the commutator at the will of the operator.

In Fig. 7 the frame, rotor, stator, windings and connections are similar to those indicated in Fig. 2. The shaft 52 revolves in bearing 94 set in the dash board 7, or any other suitable location, and in bearing 99 in a suitable support 100, said support 100 being bolted to dash board 7 by bolts 105. At one end of shaft 52 is a pulley 95 upon which travels a belt or chain 96 to pulley 97 secured upon shaft 9. Thus when shaft 9 revolves shaft 52 revolves in synchronism or in definite relation with it. Attached to the shaft 52 is arm 110 carrying brushes 55, 56, 59 and 60; brushes 55 and 59 being connected together by conductor 102 and brushes 56 and 60 being connected together by conductor 101. Base 25 is movable lon-

gitudinally of the shaft 52 but prevented from rotation by the bolts 105 and rods 106, the latter mechanically connected to the cross piece 108 carrying the handle 107. Segments 45, 47, 49 and 51 and slip rings 53 and 54 are secured to the insulating piece 25, and are held away from the brushes 55, 56, 59 and 60 by the springs 109. Slip ring 54 is connected to one terminal of the source 27 by conductor 57, and slip ring 53 is connected through conductor 58 to the contact 37 of switch 22. When the handle 107 is pushed inwardly in opposition to springs 109, brushes 55 and 56 are engaged by slip rings 53 and 54 respectively. Brushes 59 and 60 are connected to the commutator segments 45, 47, 49 and 51 depending upon the position of the armature 110. As shown brush 59 is in electrical connection with segment 51 and brush 60 is in electrical connection with brush 47. Now if switch 22 is closed, the current will flow through Fig. 2. As to the stator windings, the current will flow from the source 27 through conductor 57 to slip ring 54, to brush 56, to brush 60, to segment 47, through conductor 46, to the point *a* and thence to the stator windings to the point *b*, as previously described in connection with Fig. 2, then by conductor 50 to segment 51, to brush 59, to brush 55, to slip ring 53, through conductor 58 to the other terminal of the source 27. The reactions between rotor and stator will cause the rotor to revolve in clock-wise direction and so revolving will drive the shaft 9 which will revolve shaft 52 and the brush holder will shift so that the brush 60 will connect with the segment 49 and brush 59 will connect with segment 45. The field in the stator is correspondingly shifted and the reactions between rotor and stator will continue until the engine is started, when the handle 107 may be released and brushes and commutator segments mechanically and electrically disconnected by springs 109. As the engine continues to run the brushes may be rotated, but, being out of contact with the commutator segments, the wear of brushes and commutator segments is avoided, as these are in mechanical and electrical connection only while the engine is being started.

The commutator of the rotating armature and the brushes of an ordinary motor for self starting are always in mechanical and electrical connection. The commutator brushes of the stator of my starter may be put in mechanical and electrical connection and separated at will, thus saving wear when not in use. This principle applies whether one of the elements of the commutator revolves synchronously with the shaft of the starter or not. If however both commutator and brushes are stationary when 130

not in use when starting there will be no wear, and it is not necessary to separate them mechanically and electrically.

It is to be understood that my invention is not limited to a stator which is provided with the concentrated poles or windings as shown, but that a stator having a great number of sections of windings may be employed, similar to a direct current armature winding, in which case, the number of segments in the switching apparatus or commutator apparatus will be correspondingly increased with the result that the maxima and minima of the resulting torque curves will not be so contrasted as in the case of the apparatus illustrated, but will have a characteristic torque curve which is more nearly a straight line, that is, indicating a more nearly uniform torque. Nor do I wish to be limited to apparatus for starting an explosive engine of any particular type or number of cylinders, for my invention is broadly applicable to all types of explosive engines, and in fact to any other devices which, for starting, must be turned over or cranked.

I prefer that the windings upon the rotor of my starter shall be relatively coarse and be traversed by relatively heavy current, while the windings on the stator shall be traversed by relatively small current. In such case, since continuous slip rings continuously in connection with brushes are employed, there will be no sparking at these members notwithstanding the rotor is traversed by heavy current.

It is to be further understood that I may use separate sources of energy, one for energizing the stator and another for energizing the rotor. Or the stator may be subjected to either the entire or less than the entire electric pressure of the source and the stator may be subjected to either less than the entire or the entire pressure of the source.

While I have illustrated the rotor as directly connected upon the engine shaft 9, it is to be understood that it may be connected to the engine shaft through any suitable gearing, belting, or otherwise; and it is to be further understood there may intervene between the engine shaft and the rotor a clutch if desired. And it is to be further understood that the arrangements of Figs. 2, 3, 4, and 7 are not limitative of my invention, for it is obvious, in view of the disclosure of these figures, combinations of rotor and stator windings of different numbers and modes of connection may be employed.

What I claim is:

1. The combination with an explosive engine, of means for starting the same comprising a rotor and stator, a winding on the said rotor producing a magnetic field of substantially constant direction with respect

to said rotor in all its positions, a stator winding, and switching mechanism remote from said stator controlling said stator winding, whereby the axis of the magnetic field produced by said stator winding is progressively shifted with respect to said stator, said rotor and stator fields producing non-uniform torque having a maximum substantially simultaneously with maximum opposing engine torque.

2. The combination with an explosive engine, of means for starting the same comprising a rotor and stator, a winding on said rotor producing a magnetic field of substantially constant direction with respect to said rotor in all its positions, a stator winding, and switching mechanism having a member movable independently of said rotor controlling said stator winding, whereby the axis of a magnetic field produced by said stator winding is progressively shifted with respect to said stator, said rotor and stator reacting on each other to produce non-uniform torque having a maximum substantially simultaneously with maximum opposing engine torque.

3. The combination with an explosive engine, of means for starting the same comprising a rotor and stator, a winding on said rotor producing a magnetic field of substantially constant direction with respect to said rotor in all its positions, a stator winding, said rotor and stator reacting on each other to produce non-uniform torque having a maximum substantially simultaneously with maximum opposing engine torque, and switching mechanism having two movable members, one member movable independently of said rotor, and one member moving in synchronism with said rotor, whereby the axis of the magnetic field produced by said stator winding is progressively shifted with respect to said stator.

4. The combination with an explosive engine, of means for starting the same comprising a rotor and stator, a winding on said rotor producing a magnetic field of substantially constant direction with respect to said rotor in all its positions, a stator winding, switching mechanism having two movable members, one member movable independently of said rotor, and one member moving in synchronism with said rotor, whereby the axis of the magnetic field produced by said stator winding is progressively shifted with respect to said stator, and means for disengaging said movable members from each other.

5. The combination with an explosive engine, of means for starting the same comprising a rotor and stator, a winding on said rotor producing a magnetic field of substantially constant direction with respect to said rotor in all its positions, a stator winding, switching mechanism having two mov-

able members, one member movable independently of said rotor, and one member moving in synchronism with said rotor, whereby the axis of the magnetic field produced by said stator winding is progressively shifted with respect to said stator, and means normally holding said movable members disengaged from each other.

6. The combination with an explosive engine, of means for starting the same comprising a rotor and stator, a winding on said rotor producing a magnetic field of substantially constant direction with respect to said rotor in all its positions, a stator winding, switching mechanism having two movable members, one member movable independently of said rotor, and one member moving in synchronism with said rotor, whereby the axis of the magnetic field produced by said stator winding is progressively shifted with respect to said stator, means normally holding said movable members disengaged from each other, and means for bringing said movable members into engagement with each other.

7. The combination with an explosive engine, of a starter therefor comprising electro-dynamically reacting rotor and stator exerting on said engine a torque fluctuating in magnitude and attaining a maximum substantially simultaneously with a maximum opposing torque of said engine, means for passing uncommutated current through said rotor, and means remote from said stator for commutating the current in said stator.

8. The combination with an explosive engine, of a starter therefor comprising electro-dynamically reacting members exerting on said engine a torque fluctuating in magnitude and attaining a maximum substantially simultaneously with a maximum opposing torque of said engine, and switching mechanism independent of said members controlling their relative movement.

45 9. The combination with an explosive engine, of a starter therefor comprising electro-dynamically reacting members exerting on said engine a torque fluctuating in magnitude and attaining a maximum substantially simultaneously with a maximum opposing torque of said engine, and switching mechanism independent of said members controlling the direction and rate of fluctuation of their torque.

55 10. The combination with an explosive engine, of starting means therefor comprising a rotor and stator, rotor and stator windings, means for maintaining current flow through the rotor winding in fixed relation thereto, and switching mechanism having a movable member independent of said rotor for progressively changing the relations of the stator windings, said rotor and stator reacting on each other to produce 60 non-uniform torque having a maximum sub-

stantially simultaneously with maximum opposing engine torque.

11. The combination with an explosive engine, of means for starting the same comprising a rotor and stator, rotor and stator windings, means for passing through the rotor winding a relatively large non-commutated current, and a commutator controlling the stator winding comprising a fixed member and a movable member movable independently of said rotor, said rotor and stator reacting on each other to produce non-uniform torque having a maximum substantially simultaneously with maximum opposing engine torque.

75 12. The combination with an explosive engine, of means for starting the same comprising a rotor and stator, a winding on said rotor producing a magnetic field of substantially constant direction with respect to said rotor in all its positions, a stator winding, switching mechanism having two members movable into and out of engagement with each other, one member movable independently of said rotor, and one member moving in synchronism with said rotor, whereby the axis of the magnetic field produced by said stator winding is progressively shifted with respect to said stator, said rotor winding carrying a relatively large non-commutated current and the current in said stator winding controlled by said switching mechanism being relatively small.

80 13. The combination with an explosive engine, of means for starting the same comprising a rotor and stator, a winding on said rotor, slip rings movable with said rotor and connected to said winding, a stator winding, and switching mechanism therefor and remote therefrom comprising a plurality of non-rotating segments, co-operating rotating brushes, and slip rings in electrical communication with said brushes, said rotor and stator reacting on each other to produce non-uniform torque having a maximum substantially simultaneously with maximum opposing engine torque.

85 14. The combination with an explosive engine, of means for starting the same comprising a rotor and stator, a winding on said rotor, slip rings movable with said rotor and connected to said winding, a stator winding, switching mechanism therefor and remote therefrom comprising a plurality of stationary segments, co-operating rotating brushes, and slip rings in electrical communication with said brushes, and means normally holding said brushes and segments separated from each other.

90 15. The combination with an explosive engine, of means for starting the same comprising a rotor and stator, a winding on said rotor, slip rings movable with said rotor and connected to said winding, a stator winding, switching mechanism therefor and remote 95

therefrom comprising a plurality of stationary segments, coöperating rotating brushes, slip rings in electrical communication with said brushes, means normally holding said 5 brushes and segments separated from each other, and means for bringing said brushes and segments into engagement with each other.

16. The combination with an explosion engine exerting non-uniform torque, of means for driving the same in starting comprising a rotor connected to the shaft of said engine and a stator, said rotor and stator producing magnetic fields re-acting on each other to 15 produce a non-uniform torque attaining a maximum substantially simultaneously with a maximum opposing engine torque, slip rings and brushes for said rotor juxtaposed thereto, and switching mechanism remote 20 from said stator for progressively shifting the magnetic field of said stator.

17. The combination with an explosion engine, of means for driving the same comprising a rotor and a stator, a stator winding, and switching mechanism controlling 25

said stator winding for progressively shifting the stator field, said switching mechanism comprising rotatable and non-rotatable members normally disengaged from each other, and means for engaging said members 30 with each other.

18. The combination with an explosion engine, of means for starting the same comprising a rotor and a stator, a stator winding, switching mechanism remote from said 35 stator controlling said winding for progressively shifting the stator field, said switching mechanism comprising rotatable brushes, and coöperating non-rotatable segments connected to said winding, and means for bringing said brushes into engagement with said segments and for disengaging said brushes from said segments.

In testimony whereof I have hereunto affixed my signature in the presence of the two 45 subscribing witnesses.

ROBERT C. HULL.
